M. A. GERSON

CLOCK

Filed July 20, 1926

UNITED STATES PATENT OFFICE.

MAX A. GERSON, OF JERSEY CITY, NEW JERSEY.

CLOCK.

Application filed July 20, 1926. Serial No. 123,628.

My invention relates to a new and improved self-winding electrical clock.

One of the objects of my invention is to devise an electrical clock of simple and efficient construction in which electrical mechanism automatically winds up the spring means used for actuating the time mechanism and also the striking mechanism.

Another object of my invention is to devise a clock of this type which can be operated by means of dry cells and which will require a minimum amount of electrical energy and a minimum number of dry cells.

Another object of my invention is to devise a clock of this type having simple and compact control mechanism for both the movement and striking members of the clock.

Other objects of my invention will be set forth in the following description and drawings which illustrate a preferred embodiment thereof, it being understood that the above general statement of the objects of my invention is intended merely to generally explain the same and not to limit it in any manner.

Fig. 1 is a front elevation.

Fig. 2 is a section on the line 2—2 of Fig. 1.

Fig. 3 is a view similar to Fig. 2 but showing the circuit open.

Fig. 4 is a bottom plan view of Fig. 1.

Electrically actuated clocks have been previously proposed as, for example, in U. S. Patent No. 703,953, but the control mechanism for clocks of this type has been complicated and unsatisfactory.

Since certain fundamental parts of an electrically actuated clock are in themselves known, I have only illustrated such essential parts as are necessary for the complete understanding of my invention.

The plate 15 is suitably mounted in the clock casing and it is provided with a barrel 10 which is revolutely mounted upon the base plate 15. The barrel 10 is revolutely and loosely mounted upon the shaft 11' in the well known manner and this barrel 10 is also connected to one end of a spiral spring S, the other end of the said spiral spring being connected in the well known manner to the shaft 11', so that when the barrel 10 is turned to wind up the spring S, the said spring S causes the revolution of the shaft 11'. The shaft 11' is connected by means of suitable gears to the time indicating mechanism of the clock. The barrel 10 is connected to a gear 11 and this gear 11 meshes with a gear

14. A ratchet wheel R is mounted upon the shaft of the gear 14 and the ratchet wheel R is actuated by means of a lever 12 loosely mounted upon the shaft of the gear 14, the said lever 12 being provided with a pawl 12' so that when the said lever 12 is oscillated, it intermittently turns the ratchet wheel R in one direction and thus intermittently causes the gear 11 to be turned in one direction. A second pawl 15' prevents the reverse movement of the ratchet wheel R.

A control disk 3 is mounted upon the shaft 11' so that it turns in unison therewith. This disc 3 revolves once in twelve hours and is equivalent to the twelve hour wheel of a clock. The control disk 3 is provided with eight outer slots 1 which may be designated as time control slots, and the said control disk 3 is also provided with four inner slots 2, which may be designated as striking control slots.

Switch levers 6 and 6' are pivotally connected at 5 and 5' to arms projecting from the base plate 15. These switch levers 6 and 6' are provided with wires or conductors 16 and 16' and the said conductors 16 and 16' are connected to the respective ends of the coils of electromagnets M and M'.

A battery B has a wire or lead M² which is permanently connected to the other ends of the said electromagnetic coils. The connection between wire M² and the adjacent terminal of electromagnet M' is completed by a wire 30. Hence, when the circuit of battery B is closed, by either the switch lever 6 or by the switch lever 6', the current passes through one of the said electromagnetic coils and energizes one of them.

The switch levers 6 and 6' are laterally extended as shown in Fig. 4, and their laterally extended ends are adapted to contact with the arms 9 and 9' of a central contact member which is mounted upon an insulated support 10'. The said central contact member is connected by means of a wire 7 to one terminal of the battery B. The wire 7 is connected to the central contact member by means of a screw 8, as shown in Fig. 1.

The levers 6 and 6' are provided with upper extensions 4 and 4' and these have bevelled ends which are adapted to co-operate with the slots in the control disk 1 so that the switch levers 6 and 6' can be moved to close the circuit of the battery B, as shown in Fig. 2, or they can be moved so as to open the circuit of the battery B, as

shown in Fig. 3. Blade springs 20 are provided for continuously urging the switch levers to the circuit closing position. When the extension 4 of the lever 6 has its bevelled 5 end adjacent one of the slots 1, the said switch lever 6 is free to move to the circuit closing position so as to energize the coil of the electromagnet. Since, however, the control disk 3 is continuously moved in the 10 clockwise direction as indicated by the arrow in Fig. 1, the switch lever 6 only remains in the circuit closing position for a short and predetermined period, because the top of the slot 1 forces the bevelled end of 15 the extension 4 laterally, thus moving the parts to the circuit opening position shown in Fig. 3. Hence, the lever 6 acts to close the circuit of the battery B for eight short equal and predetermined intervals of time 20 for each complete revolution of the control disk 3. The control disk 3 makes a complete revolution in 12 hours.

The extension 4' of the switch lever 6' is of a similar construction so that the switch lever 6' remains in the circuit closing position for four short equal and predetermined periods of time during each revolution of the control disk 3. Due to the relative staggered positions of the slots 1 and 2, the 30 switch lever 6' is moved to the circuit closing position only when the corresponding lever 6 is in the circuit opening position.

The armature A' of the electromagnet M is adapted to cause the rapid vibration of 35 the member 16 in the well known manner, since the oscillation of said armature makes and breaks the circuit. Hence, when the coil of the electromagnet M is energized, the rapid oscillation of the member 16 causes 40 a corresponding rapid oscillation of the lever 12 so that the barrel 10 is moved to wind up the spiral spring S.

Since the striking mechanism requires less 45 energy than the time-indicating mechanism, I have only provided four slots 2, in contradistinction to the eight slots 1. When the lever 6' is in the circuit closing position, the striking mechanism is wound up, and when the lever 6 is in the circuit closing 50 position, the time-indicating mechanism is wound up.

The spring for the striking mechanism has a barrel having a gear wheel 33 which

meshes with a gear wheel 34 actuated by a lever 31 which is actuated by armature A. 55 The mechanism is the same as that previously illustrated.

Hence, a single control causes the proper winding up of the springs for the striking mechanism and the time indicating mechanism. Since the striking mechanism requires less energy than the time-indicating mechanism, there are more slots 1 than slots 2. The slots 1 and 2 are equivalent to cam means. For convenience, the springs of the 60 clock may be termed the time spring and the striking spring. When a battery of the ordinary dry cell type, as illustrated herein, is used for winding up the mechanism of a clock it is desirable that electric power 65 should be delivered intermittently by the battery for short periods, so as to enable the polarizing substance to act most efficiently. According to my invention power is drawn from the battery B to wind up the 70 time spring, in a series of short and uniformly separated periods, and power is drawn from the battery B to wind up the striking spring, in an intermediate series of short and separated periods. Hence, the 75 life of the battery is longer than if power was taken therefrom to simultaneously wind up the striking spring and the time spring.

I claim:

In a clock, the combination of a disc connected to the time-train, said disc having two series of spaced perforations, arranged in staggered relationship, two switch levers associated with said disc and having heads adapted to enter said perforations, said 90 heads having inclined ends so that the movement of said disc moves said heads outwardly and out of said slots, means adapted to turn said levers to force said heads inwardly, two electromagnets having separate 95 make and break armatures, the said switch levers closing the circuits of their respective magnets when their heads are in the inner position, the said armatures being respectively connected to means for respectively winding up the striking spring and the time spring.

In testimony whereof I affix my signature.

MAX A. GERSON,
